SAFETY DEVICE

Harvey C. Miller, Charleston, W. Va., assignor
to Libbey-Owens-Ford Glass Company, To-
ledo, Ohio, a corporation of Ohio

Application September 29, 1932
Serial No. 635,306

21 Claims. (Cl. 105—367)

The present invention relates broadly to improvements in safety apparatus and more particularly to a device designed primarily for use in the loading of glass sheets or other flat sheets or plates into freight cars, the principal object of the invention being to provide a novel and improved form of device which will function to safeguard the workmen loading the car by preventing the glass sheets or the like from falling forwardly toward the center of the car and upon the workmen engaged in the stacking of the sheets therein.

Other objects and advantages of the invention will become more apparent during the course 15 of the following description when taken in connection with the accompanying drawings.

In the drawings forming a part of this application and wherein like numerals are employed to designate like parts throughout the 20 same,

Fig. 1 is a transverse sectional view through a freight car disclosing, in elevation, a safety device constructed in accordance with the instant invention,

Fig. 2 is a plan view of a pair of the improved safety devices,

Fig. 3 is a section taken substantially on line 3—3 of Fig. 2, and

Fig. 4 is a section taken substantially on line 30 4—4 of Fig. 3.

Referring now to the drawings, the letter A designates a freight car within which the glass sheets or other flat sheets or plates 10 are adapted to be packed for shipping, and B the improved safety devices herein provided for maintaining the sheets 10 in position and for preventing them from falling forwardly toward the center of the freight car and upon the workmen engaged in the stacking of the said sheets in 40 place.

The freight car A has been disclosed simply by way of illustrating the present invention and may be of any conventional construction including a horizontal bottom 11, vertical side walls 12 and 13, and a top 14. Disposed within the car at each side thereof are a plurality of spaced vertical strips 15 secured to and maintained spaced from the adjacent side wall of said car by blocks 16 and against which the glass sheets 10 are adapted to be stacked. The inner faces of these strips 15 may be covered with felt or some other suitable material, if desired, to protect the glass sheets resting thereagainst.

Each safety device B embodies a main horizontal supporting structure or bridge 17 extend-

ing transversely within the car A and adapted to be positioned above the upper edges of the glass sheets 10. The supporting structure 17 consists of three longitudinally extending spaced parallel and preferably wooden strips or members 18, 19 and 20 which are maintained in properly spaced relation relative to one another at each end thereof by means of the spacing blocks 21 positioned between the said strips and secured in place by the transverse bolts 22 which pass 60 through both the strips and blocks. The strips 18, 19 and 20 are also maintained properly spaced from one another at substantially the centers thereof by the spacing blocks 23, suitable fastening elements 24 passing transversely through the 70 said strips and blocks whereby to secure them together.

Carried at each end of the supporting structure 17 and at the opposite sides thereof are the angle brackets 25 and 26 respectively extending in 75 opposite directions and having welded or otherwise secured thereto nuts or the like 27 and 28 through which are threaded the bolts 29 and 30 respectively, each of said bolts being pointed at its forward end as indicated at 31 and provided 80 at its opposite or rear end with a hand wheel 32. The angle brackets 25 and 26 may be secured to the supporting structure 17 by means of the bolts 22 which, as pointed out above, also serve to tie the strips 18, 19 and 20 and spacing 85 blocks 21 together. When it is desired to position the safety device B within the car A, the supporting structure 17 is simply held at the proper height within the car and the bolts 29 and 30 at each end thereof then threaded through the 90 nuts 27 and 28 so that the pointed ends 31 of the said bolts engage or bite into the side walls of the car as shown in Figs. 1 and 2.

Carried by the horizontal supporting structure 17 at each side of the longitudinal center there- 95 of are a plurality, and as here shown three, safety or sheet retaining units 33, 34 and 35 respectively. Each of these units comprises a pair of spaced vertical and preferably wooden arms 36 and 37 carried by and depending from the sup- 100 porting structure 17. Thus, the upper ends of these arms 36 and 37 are received between the spaced strips 18, 19 and 20 as best shown in Fig. 2 and are secured thereto by suitable fas- 105 tening elements 38. The three safety or sheet retaining units 33, 34 and 35 at each end of the supporting structure 17 are also preferably braced intermediate their upper and lower ends by an inclined bracing strip 39 which is received 110 between the spaced arms 36 and 37 of each unit.

and to which the said arms are bolted as at 40, said bracing strip being also secured at its upper end to the supporting structure 17 by fastening elements 41.

5 The vertical depending arms 36 and 37 of each safety unit 33, 34 and 35 are provided at their lower ends with the substantially U-shaped metal caps 42 and 43 respectively which fit about the said arms and are nailed thereto as indicated at 44. Received between the lower ends of each 10 pair of arms 36 and 37 is a dog or catch member 45 pivotally mounted intermediate its ends upon a horizontal bolt or pin 46 passing transversely through the said arms 36 and 37 and the 15 respective metal caps 42 and 43. The dog 45 is mounted upon the bolt 46 in such a manner that the forward end 47 thereof overbalances the rear end 48 whereby the said dog will be normally maintained in an inclined position as shown in 20 full lines in Fig. 4. In other words, the pivot point 46 is offset with respect to the longitudinal center of the dog or catch member 45, with the result that the longer forward end 47 thereof naturally tends to overbalance the shorter rear end 48. Positioned between the vertical arms 36 25 and 37 of each safety unit 33, 34 and 35 and beneath the bracing strip 39 is a relatively hard wooden block 49 secured in place by bolts or the like 50 and having a lower bevelled edge 51 30 against which the end 48 of dog 45 is adapted to abut so as to maintain the said dog in the proper inclined position. The forward end edge of each dog 45 is preferably bevelled as at 52 35 to provide a substantially vertical face when the said dog is in its normally inclined position and against which the glass sheet is adapted to abut should it fall forwardly.

In the loading of relatively large sheets of glass within a freight car, it is customary to stack 40 a pile of sheets against each side of the car and secure them firmly in place for shipping by means of suitable ropes or metal bands which are passed horizontally in front of each stack of sheets and fastened to the adjacent side wall 45 of the car. More specifically, it is customary, in packing the glass sheets within the freight car, to first jack up one side of the car so that the side walls thereof are slightly inclined. The glass sheets are then stacked one at a time against the 50 lower inclined side wall of the car or, in other words, against that side which is not jacked up. After the desired pile of sheets has been thus stacked, they are firmly secured in place for shipping in the manner above described. The 55 opposite side of the car is then jacked up and the glass sheets piled against the other side of the car in the same manner. Thus, there is provided a stack of sheets at each side of the car, with a space or aisle therebetween, such aisle 60 being necessary in order to permit access to the glass sheets when they are to be unpacked. It is also the usual practice to place a sheet of paper between each sheet of glass so that the glass sheets do not come in direct contact with one another. 65 Workmen have been seriously injured in the past as a result of the glass sheets falling forwardly upon them during the stacking of the said sheets in place. For instance, it not infrequently happens that a workman, in pulling out two or three 70 sheets of glass in order to place the sheets of paper therebetween, will have the suction between the sheets pull the balance of the pile of sheets forwardly upon him, resulting not only in serious injury to his person, but also in the 75 breakage of the glass. The present invention has

been especially designed to safeguard the workmen engaged in loading the car by preventing the glass sheets from falling forwardly upon them, as a result of which the liability of the workmen being injured during the packing of the car will be greatly lessened. 80

In the use of the present invention, one or any suitable number of safety devices B may be employed, and these devices are secured within the freight car A above the glass sheets 10 in the manner above described. That is to say, the transverse supporting structure 17 of each safety device is secured in position within the car by means of the bolts 29 and 30 which are caused to engage and bite into the side walls of said car. 85 The supporting structure 17 is arranged at such a height within the car so that the lower ends of the pivoted dogs 45 will project slightly below the upper edges of the glass sheets. The dogs 45 of the safety or sheet retaining units 33, 34 and 35 at each side of the longitudinal center of the supporting structure 17 are mounted so that the lower ends thereof project toward the respective side wall of the car. Therefore, as each sheet of glass is placed in position against the side 90 wall of the car, the upper edge of the sheet engaging the lower ends of the dogs 45 will cause the said dogs to be swung upwardly to a substantially horizontal position as indicated by the broken lines in Fig. 4 to permit the stacking 100 of the glass sheets in place. After each sheet has been slipped beneath the dogs, the said dogs will again fall downwardly into an inclined position by gravity, and the said dogs will be maintained in such inclined position and prevented 110 from swinging in the opposite direction by means of the wooden blocks 49. As a consequence, should one of the glass sheets fall forwardly as shown at 10a in Fig. 1, it will engage the first 115 inclined dog 45 and be prevented thereby from falling forwardly upon and injuring the workmen engaged in stacking the sheets within the car. In the event only a few sheets of glass have been placed in position, and should they fall forwardly, they will be caught by the dog 45 of the first safety unit 33, whereas if a greater number of sheets have been stacked in place, they will be caught by the dog 45 of the second safety unit 34 or by the dog of the third safety unit 35. After the requisite number of sheets have been 125 stacked against each side of the car and secured in position in the manner above described, the safety devices B are removed. The number of safety devices employed will depend upon the 130 width of the glass sheets being packed, with two or more being ordinarily used, while the height at which the safety devices are positioned within the car will depend upon the height of the glass sheets being packed. As brought out above, the improved safety devices herein provided are 135 not restricted to use in the packing of glass sheets but, on the contrary, may also be utilized in the packing of other flat sheets or plates.

It is to be understood that the form of the 140 invention herewith shown and described is to be taken as the preferred embodiment of the same, and that various changes in the shape, size and arrangement of parts may be resorted to without departing from the spirit of the invention or 145 the scope of the subjoined claims.

I claim:

1. In safety apparatus of the character described, the combination with a freight car with- 150 in which a plurality of sheets of glass or the like

- are adapted to be stacked upon edge against each side wall thereof, of a safety device arranged within the car and carried thereby in a position above the glass sheets, said safety device including a plurality of pivotally mounted dogs, the lower ends of which project downwardly beyond the upper edges of the glass sheets to prevent the said sheets from falling forwardly. 80
2. In safety apparatus of the character described, the combination with a freight car within which a plurality of sheets of glass or the like are adapted to be stacked upon edge against each side wall thereof, of a safety device arranged within the car and carried thereby in a position above the glass sheets, said safety device including a plurality of pivotally mounted dogs, the lower ends of which project downwardly beyond the upper edges of the glass sheets to prevent the said sheets from falling forwardly, said dogs being mounted in such a manner that one end thereof overbalances the opposite end whereby the dogs are normally maintained in an inclined position. 85
3. In safety apparatus of the character described, the combination with a freight car within which a plurality of sheets of glass or the like are adapted to be stacked upon edge against each side wall thereof, of a safety device arranged within the car and carried thereby in a position above the glass sheets, said safety device including a plurality of pivotally mounted dogs, the lower ends of which project downwardly beyond the upper edges of the glass sheets to prevent the said sheets from falling forwardly, said dogs being mounted in such a manner that one end thereof overbalances the opposite end whereby the dogs are normally maintained in an inclined position. 90
4. In safety apparatus of the character described, the combination with a freight car within which a plurality of sheets of glass or the like are adapted to be stacked upon edge against each side wall thereof, of a safety device arranged within the car and carried thereby in a position above the glass sheets, said safety device including a plurality of pivotally mounted dogs, and means for normally maintaining said dogs in a vertically inclined position, with the lower ends thereof projecting downwardly beyond the upper edges of the glass sheets to prevent the said sheets from falling forwardly. 95
5. In safety apparatus of the character described, the combination with a freight car within which a plurality of sheets of glass or the like are adapted to be stacked upon edge against each side wall thereof, of a safety device arranged within the car and carried thereby in a position above the glass sheets, said safety device including a plurality of pivotally mounted dogs, the lower ends of which project downwardly beyond the upper edges of the glass sheets to prevent the said sheets from falling forwardly, and means for mounting the said dogs so that they may be swung about their pivots in one direction to permit the stacking of the glass sheets in place and prevented from swinging in the opposite direction. 100
6. In safety apparatus of the character described, the combination with a freight car within which a plurality of sheets of glass or the like are adapted to be stacked upon edge against each side wall thereof, of a safety device arranged within the car and carried thereby in a position above the glass sheets, said safety device including a plurality of pivotally mounted dogs, the lower ends of which project downwardly beyond the upper edges of the glass sheets to prevent the said sheets from falling forwardly, the pivot point of each dog being offset with respect to the longitudinal center of said dog so that one end of the dog overbalances the opposite end thereof, and means engaging the shorter end of the dog to normally maintain the said dog in an inclined position. 105
7. In safety apparatus of the character described, the combination with a freight car within which a plurality of sheets of glass or the like are adapted to be stacked upon edge against each side wall thereof, of a safety device arranged within the car and carried thereby, said safety device including a transverse supporting structure mounted in a position above the glass sheets, and a plurality of pivotally mounted dogs carried by said supporting structure, the lower ends of said dogs projecting downwardly beyond the upper edges of the glass sheets to prevent the said sheets from falling forwardly. 110
8. In safety apparatus of the character described, the combination with a freight car within which a plurality of sheets of glass or the like are adapted to be stacked upon edge against each side wall thereof, of a safety device arranged within the car and carried thereby, said safety device including a transverse supporting structure mounted in a position above the glass sheets, and a plurality of pivotally mounted dogs carried by said supporting structure, the lower ends of said dogs projecting downwardly beyond the upper edges of the glass sheets to prevent the said sheets from falling forwardly, said dogs being mounted in such a manner that one end thereof overbalances the opposite end whereby the dogs are normally maintained in an inclined position. 115
9. In safety apparatus of the character described, the combination with a freight car within which a plurality of sheets of glass or the like are adapted to be stacked upon edge against each side wall thereof, of a safety device arranged within the car and carried thereby, said safety device including a transverse supporting structure mounted in a position above the glass sheets, and a plurality of pivotally mounted dogs carried by said supporting structure, the lower ends of said dogs projecting downwardly beyond the upper edges of the glass sheets to prevent the said sheets from falling forwardly, said dogs being mounted in such a manner that one end thereof overbalances the opposite end whereby the dogs are normally maintained in an inclined position. 120
10. In safety apparatus of the character described, the combination with a freight car within which a plurality of sheets of glass or the like are adapted to be stacked upon edge against each side wall thereof, of a safety device arranged within the car and carried thereby, said safety device including a transverse supporting structure mounted in a position above the glass sheets, and a plurality of spaced safety or sheet retaining units carried thereby, each including a pair of spaced vertical depending arms, and a dog pivotally carried at the lower end of each pair of arms, the lower ends of said dogs projecting downwardly beyond the upper edges of the glass sheets. 125
- 75

sheets to prevent the said sheets from falling forwardly.

11. In safety apparatus of the character described, the combination with a freight car with-
5 in which a plurality of sheets of glass or the like are adapted to be stacked upon edge against each side wall thereof, of a safety device arranged within the car and carried thereby, said safety device including a transverse supporting struc-
10 ture mounted in a position above the glass sheets, and a plurality of spaced safety or sheet retaining units carried thereby, each including a pair of spaced vertical depending arms, and a dog piv-
15 otally carried at the lower end of each pair of arms, the lower ends of said dogs projecting downwardly beyond the upper edges of the glass sheets to prevent the said sheets from falling forwardly, said dogs being mounted in such a manner that one end thereof overbalances the oppo-
20 site end whereby the dogs are normally maintained in an inclined position.

12. In safety apparatus of the character de-
scribed, the combination with a freight car with-
25 in which a plurality of sheets of glass or the like are adapted to be stacked upon edge against each side wall thereof, of a safety device arranged within the car and carried thereby, said safety device including a transverse supporting struc-
30 ture mounted in a position above the glass sheets, and a plurality of spaced safety or sheet retain-
35 ing units carried thereby, each including a pair of spaced vertical depending arms, a dog pivotally carried at the lower end of each pair of arms, the lower ends of said dogs projecting down-
40 wardly beyond the upper edges of the glass sheets to prevent the said sheets from falling forwardly, said dogs being mounted in such a manner that one end thereof overbalances the opposite end whereby the dogs are normally maintained in an inclined position, and means for permitting the dogs to be swung in one direction out of their inclined position but prevented from swinging in the opposite direction from such position.

13. In safety apparatus of the character de-
scribed, the combination with a freight car with-
45 in which a plurality of sheets of glass or the like are adapted to be stacked upon edge against each side wall thereof, of a safety device arranged within the car and carried thereby, said safety device including a supporting structure extending transversely within said car and mounted in a position above the glass sheets, a plurality of safety or sheet retaining units carried by the transverse supporting structure at each side of the longitudinal center thereof, each of said units including a pivotally mounted dog, the lower end of which projects downwardly beyond the upper edges of the glass sheets to prevent the said sheets from falling forwardly, the pivoted dogs of the safety units at the opposite sides of the longitudinal center of said supporting structure projecting in opposite directions and toward the respective side wall of said car.

14. In safety apparatus of the character de-
65 scribed, the combination with a freight car with-
in which a plurality of sheets of glass or the like are adapted to be stacked upon edge against each side wall thereof, of a safety device arranged within the car and carried thereby, said safety device including a supporting structure extending transversely within said car and mounted in a position above the glass sheets, a plurality of safety or sheet retaining units carried by the transverse supporting structure at each side of the longitudinal center thereof, each of said units

including a pair of spaced parallel depending arms carried at their upper ends by the supporting structure, and a dog pivotally carried at the lower end of each pair of arms and mounted in a manner to normally assume a vertically inclined position, the lower ends of said dogs extending downwardly beyond the upper edges of the glass sheets to prevent the said sheets from falling forwardly, the dogs of the safety units at the opposite sides of the longitudinal center of said supporting structure projecting in opposite directions and toward the respective side wall of the car.

15. A safety device of the character described, including a longitudinally extending supporting structure adapted to be arranged in a substantially horizontal position, and a plurality of dogs pivotally carried thereby and normally main-
90 tained in a vertically inclined position when the supporting structure is disposed in a substantially horizontal position.

16. A safety device of the character described, including a longitudinally extending supporting structure adapted to be arranged in a substantial-
100 ly horizontal position, and a plurality of safety units carried by said supporting structure and each including a pair of spaced parallel arms ex-
105 tending at substantially right angles with respect thereto, and a dog pivotally carried by each pair of arms, said dogs being normally main-
tained in a vertically inclined position when the supporting structure is disposed in a substan-
tially horizontal position.

17. A safety device of the character described, including a longitudinally extending supporting structure adapted to be maintained in a substan-
110 tially horizontal position, and a plurality of dogs pivotally carried thereby, said dogs being mounted in such a manner that one end thereof over-
115 balances the opposite end whereby the dogs are normally maintained in a vertically inclined posi-
tion when the supporting structure is disposed in a substantially horizontal position.

18. A safety device of the character described, including a longitudinally extending supporting structure adapted to be maintained in a substan-
120 tially horizontal position, a plurality of dogs pivotally carried thereby, said dogs being mounted in such a manner that one end thereof over-
125 balances the opposite end whereby the dogs are normally maintained in a vertically inclined posi-
130 tion when the supporting structure is disposed in a substantially horizontal position, and means for permitting the dogs to be swung in one direction out of their inclined position but pre-
135 vented from swinging in the opposite direction from such position.

19. A safety device of the character described, including a longitudinally extending supporting structure adapted to be arranged in a substan-
135 tially horizontal position, and a plurality of safety units carried thereby, each including a pair of spaced parallel arms arranged at substantially right angles with respect to said supporting struc-
140 ture, and a dog pivotally carried by each pair of arms, said dogs being mounted in such a manner that one end thereof overbalances the opposite end whereby the dogs are normally maintained in a vertically inclined position when the supporting structure is disposed in a substantially horizontal position.

20. A safety device of the character described, including a longitudinally extending supporting structure adapted to be arranged in a substan-
145 tially horizontal position, and a plurality of safety
